UNITED STATES PATENT OFFICE.

HOWARD S. KENNEDY AND CHARLES M. CONNOLLY, OF TROY, NEW YORK, ASSIGNEES,
BY MESNE ASSIGNMENTS, TO CLUETT, PEABODY & CO., INC., OF TROY, NEW YORK, A
CORPORATION OF NEW YORK.

OPEN-BOSOM DRESS-SHIRT.

1,141,397.

Specification of Letters Patent.

Patented June 1, 1915.

Application filed June 16, 1911. Serial No. 633,472.

To all whom it may concern:

Be it known that we, HOWARD S. KENNEDY and CHARLES M. CONNOLLY, each a citizen of the United States, residing at 5 Troy, county of Rensselaer, and State of New York, have invented certain new and useful Improvements in Open-Bosom Dress-Shirts, of which the following is a specification.

10 The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a plan view of 20 the bosom-portion of a dress-shirt embodying the invention. Fig. 2 is a rear plan view of a broken-away edge-portion of the inner bosom-member on a larger scale. Fig. 3 is a vertical cross-section taken on the broken line 3—3 in Fig. 2.

The principal object of the invention is to facilitate opening and closing for use the bosom of an open-bosom shirt such as a dress-shirt.

30 In dress-shirts having stiffly starched open bosoms, much difficulty is experienced in inserting and removing the studs which are inserted through buttonholes in the bosom-members along their lapping edges to hold the same together. This is particularly true with regard to the buttonholes near the center of the bosom where it is difficult or impossible for a thumb and finger of the same hand to grasp or manipulate the 35 stud to insert it through the lapping bosom-members.

In carrying out the invention, we make certain of the buttonholes in the inner bosom-member in the form of notches or 45 slits extending inward from the edge of the bosom-member, and terminating in an eyelet-end to receive the shank of the button. With such a construction the stud or button can be first inserted in the usual buttonhole in the outer bosom-member, and then the inner bosom-member can be drawn under the outer bosom-member to draw the shank of the button into the mouth of the notch, and therethrough into the eyelet-end which

is adapted to freely receive the shank of the 55 button.

Referring to the drawings wherein the invention is shown in preferred form, 1, represents the outer member and, 2, the inner member of the bosom of a dress-shirt 60 adapted to be worn in a stiffly starched condition.

The bosom-members may be provided at the top and bottom with means whereby they can be secured together, as buttonholes, 65 3, of the usual form. The outer bosom-member is also provided intermediately of its ends with one or more ordinary buttonholes, 4, adapted to receive detachable buttons or studs 5. The inner bosom-member 70 is provided at a point opposite each button-hole, 4, in the outer bosom-member, with a buttonhole in the form of a notch, 6, extending inward from the edge of the bosom-member, terminating in an eyelet-end, 7, 75 adapted to freely receive the shank of the stud, 5, the notch, 6, being adapted to receive the shank of the stud, 5, and guide the same into the eyelet-end, 7, as the inner bosom-member is forced toward and beneath the outer bosom-member until their 80 edges are in the proper lapping position. In this manner the middle parts of the bosom can be secured together before they are secured at either the top or the bottom; but preferably they are first secured 85 together at the bottom as by a stud, 8, upon which the bosom-members swing as they are brought together in forcing the studs, 5, into the notches 6. After the studs, 5, 90 have been located in the eyelet-ends, 7, of the notched buttonholes, the members can be secured together at the top by a stud, 9, in the usual manner.

The bosom can be opened by first removing either the stud, 8, or the stud, 9, or both, and then simply pulling the bosom-members apart sidewise to withdraw the studs, 5, out through the notches 6. Bending or wrinkling of the bosom is thus unnecessary 100 either in fastening the bosom-members together or in separating them.

To facilitate the entrance of the stud into the notch, 6, said notch may be slightly V-shaped at its mouth as shown.

105 We have shown the inner bosom-member reinforced along its edge by a fold, 10, of fabric which forms a reinforcing thickness

along the edge of the bosom approximately along the line of the outer edge of the eyelet-end, 7, as shown in Fig. 2. This fold is stitched to certain of the bosom-plies by a line of stitching, 11, and is also secured by the line of stitching, 12, whereby all of the bosom-plies are stitched together. There is thus formed at the contracted entrance to the eyelet-end, 7, at, 13, reinforced or stiffened points adapted to resist with considerable force the passage of the shank of the stud therebetween, so that accidental withdrawal of the stud from the eyelet-end is effectively prevented.

15 What we claim as new and desire to secure by Letters Patent is—

1. An open-front dress-shirt having inner and outer bosom-members provided with means for securing together said members at top and bottom, one of said means being pivotal, said outer member being provided intermediately of its ends with a stud-hole, and said inner member being provided with a notch extending inward from its edge, and terminating in an eyelet-end opposite said stud-hole in the outer member.

2. An open-front dress-shirt having inner and outer bosom-members provided

with means for securing together said members at top and bottom, one of said means being pivotal, said outer member being provided intermediately of its ends with a stud-hole, and said inner member being provided with a V-shaped notch extending inward from its edge, and terminating in an eyelet-end opposite said stud-hole in the outer member.

3. An open-front dress-shirt having inner and outer bosom-members provided with means for securing together said members at top and bottom, said outer member being provided intermediately of its ends with a stud-hole, and said inner member being provided with a notch extending inward from its edge, and terminating in an eyelet-end opposite said stud-hole in the outer member, said inner bosom-member having thickened portions adjacent to the outer side of said eyelet-end.

In testimony whereof, we have hereunto set our hands this 14th day of June, 1911.

HOWARD S. KENNEDY.
CHARLES M. CONNOLLY.
